UNITED STATES PATENT OFFICE.

EDGAR B. SYMONS, OF LOS ANGELES, CALIFORNIA, ASSIGNOR TO SYMONS BROTHERS COMPANY, OF MILWAUKEE, WISCONSIN, A CORPORATION OF SOUTH DAKOTA.

SPRING-HEAD ADJUSTMENT FOR DISK CRUSHERS.

Application filed December 22, 1924. Serial No. 757,318.

To all whom it may concern:

Be it known that I, EDGAR B. SYMONS, a citizen of the United States, residing at Los Angeles, in the county of Los Angeles and State of California, have invented a certain new and useful Improvement in Spring-Head Adjustments for Disk Crushers, of which the following is a specification.

My invention relates to a head adjustment for disk crushers and particularly to a spring head adjustment adaptable for use with horizontal disk crushers of the type in which a lenticular crushing space is defined by two opposed rotating cupped disks. Other objects will appear from time to time in the course of the specification and claims. I illustrate my invention more or less diagrammatically in the accompanying drawings wherein—

20 Figure 1 is a vertical longitudinal section; Figure 2 is a section on the line 2—2 of Figure 1; and

Figure 3 is a section on the line 3—3 of Figure 1.

25 Like parts are illustrated by like symbols throughout the specification and drawings.

A is a hollow shaft adapted to be rotated from a power source not herein shown and 30 B is a solid shaft, within the hollow shaft but inclined to it, also adapted for rotation. Mounted at the extremity of the shaft A is the socket member A¹ having the spherical bearing surface A² and terminating in the 35 outwardly projecting flange A³.

Secured to the end of the shaft B is the member B¹ having a spherical surface B² provided for example with a spherical babbitting B³. B⁴ is a circumferential outwardly projecting flange, the entire element having the conic concave surface B⁵ adapted to support the inner crushing disk C. C¹ is any suitable disk engaging washer adapted to be secured for example by means of the bolt 40 C² to the end of the shaft B and thus to hold the disk in position on the ball member B¹.

Positioned against the outer ledge or corner D of the flange A³ is the ring member 50 D¹ which has the inwardly projecting flange D² adapted to limit the inward movement of the ring member toward the crushing zone. The ring D¹ is provided with outwardly projecting spring abutments D³ upon 55 which the spiral springs D⁴ are mounted in

pairs about the circumference of the ring. D⁵ is an angle member the inner edge of which abuts against the inner corner of the flange A³. It is apertured to permit the passage of the holding bolts E about which are 60 spacing sleeves E¹ compressed between the angle element D⁵ and the circumferential ring E². E³ are removable spacing shims.

Adapted to be held by the bolts E is the centrally apertured disk supporting member 65 G, on which is mounted the outer disk G¹ which may be held in position for example by the outwardly screw threaded locking ring G² and the inwardly locking screw threaded ring G³. The head G is provided 70 with an outwardly projecting flange or flanges G⁴ through which pass the bolts E.

Slidable along the member D¹ and preferably out of contact with it, is the circumferential ring H inwardly projecting from 75 which are the outer abutments H¹ for the springs D⁴. This abutment member is expanded at intervals into the cylindrical members H², each of which is in screw threaded relation with one of the bolts E. 80

The outward movement of the ring H may be limited for example by the circumferential stop ring J which is locked in position for example by the bolts J¹ which pass through the upper edge of the member D¹ as at J².

The tension of the springs is sufficient to prevent all relative movement of the opposed disks, except the normal crushing movement caused by their rotation, as long 90 as the material normally crushed passes therebetween. If, however, a piece of iron or similar uncrushable material passes between the disks it will overcome the tension of the springs D⁴, and will separate the 95 disks and pass therebetween without damaging them.

The springs are all normally of like strength, and it is desirable to avoid the necessity of separately adjusting each 100 spring. Such separate adjustment is unnecessary with the present structure, since the spring abutment D³ is held in constant relation, throughout its periphery, with the member A¹, by its engagement, through the flange D², with the corner D. The ring H is also normally positioned by the abutment of the ends of the cylinders H² against the face of the ring D⁵, the abutments D³ being 105 of course broken away in line with the pas- 110

sage of the bolts E. Thus when the structure is set as shown, the tension of the springs is made automatically uniform throughout the circumference of the head.

5 The adjustment can be however, varied by machining off the inner ends of the cylinder members H¹.

In order to dismount the spring head it is necessary only to loosen the bolts E until 10 the ring member H contacts the limit ring J. Further extension of the springs is then impossible, they being compressed between fixed abutments, and the spring head can easily be removed.

15 If the support G and the disk G¹ are forced by the interposition of non-crushable material to recede from the cone C the normal adjustment is in no wise disturbed. The ring H moves as a unit, and, through 20 the tubular members H², moves with it the ring D⁵, and there is no change in the spatial relation between D⁵ and the flanges G⁵. Thus the spatial relation of the ring E², the spacing sleeves E¹ and the shims E³ with 25 each other and with the bolts E, the ring D⁵ and the support G, is undisturbed.

It will be realized that while I have described and shown a practical and operative device, that nevertheless many changes 30 might be made in the size, shape, number and disposition of parts without departing from the spirit of my invention, and that I wish my disclosure to be taken as in a broad sense illustrative rather than as limiting me to the specific structure described 35 and shown.

I claim:

1. In a disk crushing machine comprising 40 a pair of opposed crushing heads having a normally constant relation, a yielding release adapted to permit relative movement of said crushing heads in response to abnormal compression conditions between the opposed crushing disks, comprising a spring 45 abutment member fixed in relation to one of said disks, a spring abutment axially movable in relation to said disk, a plurality of spiral springs compressed between said abutments and connections between said 50 movable abutment and the opposite disk.

2. In a disk crushing machine comprising a pair of opposed crushing heads having a normally constant relation, a yielding release adapted to permit relative movement 55 of said crushing heads in response to abnormal compression conditions between the opposed crushing disks, comprising a spring abutment member fixed in relation to one of said disks, a spring abutment axially movable in relation to said disk, yielding means compressed between said abutments and connections between said movable abutment and the opposite disk.

3. In a disk crushing machine comprising 60 a pair of opposed crushing heads hav-

ing a normally constant relation, means for adjusting the normal distance between said heads, and a yielding release adapted to permit relative movement of said crushing heads in response to abnormal compression 70 conditions between the opposed crushing disks without disturbing their normal adjustment, comprising an abutment member fixed against movement in relation to one of said heads, an abutment member movable 75 in relation to said head, yielding means interposed between said abutments, and adjusting means interposed between said moving abutment and the opposite of said heads, said last mentioned head and abutment being adapted to move in unison and without change of their spatial relation.

4. In a disk crushing machine comprising a pair of shafts, one hollow and the other solid, the solid shaft being positioned within the hollow shaft, a crushing disk carried by said solid shaft, an opposed crushing disk carried by said hollow shaft and a yielding connection between said hollow shaft and the disk carried thereby.

5. In a disk crushing machine comprising a pair of shafts, one hollow and the other solid, the solid shaft being positioned within the hollow shaft, a crushing disk carried by said solid shaft, an opposed crushing disk supported upon said hollow shaft, and means for holding it normally against movement in relation to said hollow shaft, said means being adapted, in response to predetermined conditions of excess pressure 95 in the crushing zone, to permit movement of said disk in relation to said hollow shaft.

6. In a disk crushing machine comprising a pair of shafts, one hollow and the other solid, the solid shaft being positioned within the hollow shaft, a crushing disk carried by said solid shaft, an opposed crushing disk supported upon said hollow shaft, and means for holding it normally against movement in relation to said hollow shaft, comprising a spring abutment in fixed relation with the end of the hollow shaft, an opposed spring abutment in movable relation therewith, and a plurality of springs compressed therebetween.

7. In a disk crushing machine comprising a pair of shafts, one hollow and the other solid, the solid shaft being positioned within the hollow shaft, a crushing head at the end of said solid shaft and a crushing disk 120 carried thereby, a crushing head adapted to be supported by the hollow shaft and a crushing disk carried thereby, means for normally drawing said last mentioned crushing head and disk toward said first mentioned crushing head and disk, and means adapted to limit their approach.

8. In a disk crushing machine comprising a pair of shafts, one hollow and the other solid, the solid shaft being positioned with-

in the hollow shaft, a crushing head at the end of said solid shaft and a crushing disk carried thereby, a crushing head adapted to be supported by the hollow shaft and a crushing disk carried thereby, and means for holding said last mentioned head and disk normally in constant relation to the hollow shaft, comprising a plurality of tensional supporting members extending from said head toward said hollow shaft, and securing means therefor associated with the end of said hollow shaft.

5

10 9. In a disk crushing machine comprising

a pair of shafts, one hollow and the other solid, the solid shaft being positioned within the hollow shaft, the two shafts being held against relative axial movement, a crushing disk carried by the solid shaft, an opposed crushing disk carried by the hollow shaft and a yielding connection between the 15 hollow shaft and the disk carried thereby.

20

Signed at Chicago, county of Cook and State of Illinois, this 12th day of December, 1924.

EDGAR B. SYMONS.
